EXHAUST MANIFOLD

Application filed February 27, 1928. Serial No. 257,251.

This invention relates to manifolds used on internal combustion engines and has particular reference to a device for heating the carbureted fuel mixture before it enters the firing chamber.

Prior heating arrangements have made use of a baffle and a single valve to direct more or less of the hot exhaust gases of the exhaust manifolds to a spot on the intake manifold or 10 to a riser which extends from the carburetor past the exhaust manifold to the intake manifold.

It has been customary to direct a portion of the exhaust gases toward this hot spot or 15 riser, but as far as I am aware no prior construction has taken all of the exhaust gases controlled by a plurality of valves and directed all or a part of them against the riser at the center of the manifolds. With the 20 present arrangement it is possible to direct either half or all of the exhaust gases directly against the riser to cause a preheating. This is of advantage when the outside temperature becomes cooler for at times it is desirable to direct but a portion of the exhaust 25 gases against the riser, while at other times all the exhaust may be utilized.

The object of the invention is accomplished by causing the riser to pass through the 30 exhaust manifold and equipping the manifold at either side of the riser with a valve which may be turned directly across the manifold or swung through an angle to close an auxiliary passage which is positioned centrally longitudinally of the exhaust manifold 35 and which has for its object to conduct away the exhaust gases to the exhaust tube when the valve is across the manifold. The two valves are independently operated and it is 40 accordingly possible to have one valve across the manifold and the other across the opening of the auxiliary passage.

The invention is disclosed on the accompanying drawing in which:

45 Figure 1 shows a side view of an internal combustion engine with the new form manifold and heating arrangement applied thereto, parts of the exhaust manifold being shown in section.

50 Figure 2 is a plan view of the exhaust man-

ifold removed from the engine with parts broken away and shown in section.

Figure 3 is a section through the intake and exhaust manifold on the line 3—3 of Figures 1 and 2.

55 Figure 4 is a detail view of a modified form of valve.

Figure 5 is a sectional view at right angles to Figure 4 of the modified form adapted for operation from the dash.

60 Referring to Figure 1, the numeral 10 designates an internal combustion engine as a whole, 12 the intake manifold, 14 the exhaust manifold, and 16 the carburetor. The carburetor 16 is connected to the intake manifold 65 12 by means of a riser 18 which passes through the exhaust manifold 14, as seen from Figures 2 and 3. The riser 18 passes centrally through the exhaust manifold and is surrounded on all sides by a chamber 20, 70 which has a port 22 at its lower portion which leads to the exhaust pipe 24.

Extending centrally parallel to the exhaust 75 manifold 14 is a pair of walls 26 and 28 forming the auxiliary passage 30 therebetween to conduct the exhaust gases to the exhaust tube 24 when either or both valves 32 or 34 are across the exhaust manifold.

Positioned in the exhaust manifold at either side of the riser 18 is a pair of similar 80 valves 32 and 34 which are capable of being turned either across the path of the manifold as shown by the valve 32 or in alignment with the wall 26 to close the auxiliary passage 30, as shown by the valve 34.

85 These valves are adjusted from below as shown in Figure 1, the adjusting means comprising a holding member 35 and the bolts 37 which may be released and the valve shifted to its desired position and the bolts retightened.

90 The valves 32 and 34 are not interconnected but are capable of independent operation. It is therefore, possible to position the valves as shown in Figure 2, that is one valve may be 95 closed across the manifold while the other closes an end of the auxiliary passage. If desired, both valves may be placed across the exhaust manifold or both may be placed so as to close the end of the auxiliary passage 30. 100

The position of the valves 32 and 34 will depend on the outside temperature. When the weather is warm, as in the summer time, both valves will be placed in the position now occupied by the valve 32 in Figure 2. During extreme cold weather, or in the winter the both valves will be placed in the position of the valve 34 in Figure 2. During seasons of the year when the weather is intermediate between the extremes of heat and cold, only one valve may be moved across the exhaust manifold as shown in the position of the two valves in Figure 2.

With both valves across the manifold the exhaust from all the cylinders will be compelled to travel through the auxiliary passage 20 and to the exhaust tube 24, only such gases arriving at the riser 18, as will in their natural course flow through the port 22 to the chamber 20. When one or both of the valves 32 and 34 is closed, it will force either half or all, respectively, of the exhaust gases to impinge directly against the riser 18 and pass from the port 22 to the exhaust tube 24, giving a much greater degree of heating to the carbureted gases as they pass from the carburetor 16 to the intake manifold 12 through the riser 18.

Referring to the structure shown in Figure 4, it will be seen that as a modification the operation of the valves 32 and 34 may be controlled from the instrument board or other suitable parts of an automotive vehicle. The valve 34 is shown as mounted on a stem 36 journaled in a lower plate 38 suitably secured to the exhaust manifold and at its upper portion in a stud portion 40 formed integral with the exhaust manifold 14. The upper portion of the stem 36 is provided with a pair of washers 42 between which there is confined a coil spring 44. The end of the stem has secured therein a cotter pin 46 to hold the parts in secured relation. The opposite end of the stem 36 has secured thereon an arm 48 having an eye 50 for the application of a suitable linkage which extends to the instrument board or dash of the automotive vehicle to which the present invention is intended to be applied.

The function of the valves shown in Figures 4 and 5, is precisely the same as that shown in Figures 1 to 3 inclusive, the single difference residing in the changed structure necessary to adapt the valve to operation from the dash.

The various parts are suitably interconnected or secured by means of bolts 52 in a well known manner.

The invention is shown as applied to a six cylinder engine, the two middle exhaust ports 54 and 56 being siamesed, however, the invention is capable of adaptation to an engine of any suitable number of cylinders.

If desired, the passage 30 may be lengthened to extend past the mouths of the exhaust

ports 54 and 56 and the valves placed between the end exhaust ports 58 and 60 and the exhaust ports 54 and 56, or the passage may extend past but one mid port 54 or 56 at one side and only one valve positioned between the two ports on one side of the manifold.

I claim:

1. In combination with an internal combustion engine having intake and exhaust manifolds, a riser connected to said intake manifold and passing through said exhaust manifold, and a plurality of means in said exhaust manifold to direct all or a part of the exhaust gases against the riser.

2. The combination of claim 1, said means comprising independently operated valves, the closing of one valve across the exhaust manifold causing a part of the exhaust gases to impinge directly against the riser, the closing of both valves across the exhaust manifold preventing substantially all of the exhaust gases from impinging directly against the riser, and the opening of both valves allowing free passage of the gas through the manifold and causing substantially all of the exhaust gases to impinge against the riser.

3. In combination with an internal combustion engine having an exhaust manifold and an intake manifold positioned thereover, a riser from the carburetor passing through the exhaust manifold, and a plurality of independent means in said exhaust manifold independently operated from its under side for controlling the flow of exhaust gases about said riser, said means capable of directing all or a part of said gases from or to said riser.

4. In combination with an internal combustion engine having intake and exhaust manifolds, a riser from the carburetor to the intake manifold passing through the exhaust manifold, an auxiliary passage in the exhaust manifold to allow the exhaust gases to be by-passed away from direct contact with the riser, and means for controlling the flow of the exhaust gases through said passage.

5. The combination of claim 4, said means comprising a plurality of members controlling said passage from a plurality of points.

6. The combination of claim 4, said means comprising two valve independently controlling opposite ends of said passage.

7. The combination of claim 4, said passage positioned centrally longitudinally of said exhaust manifold and passing at one side of said riser, and said means comprising two independently operated valves controlling the ends of said auxiliary passage.

8. The combination of claim 4, said means comprising two valves, one at either end of said passage, the swinging of one valve across the exhaust manifold diverting half of the exhaust gases through said passage and the

- swinging of both valves across the exhaust manifold diverting all of the exhaust gases through said passages.
9. In combination with an internal combustion engine having intake and exhaust manifolds, a riser from the carburetor to the intake manifold passing centrally through the exhaust manifold, an auxiliary passage formed with said exhaust manifold and positioned centrally longitudinally thereof and extending to opposite sides of said riser, a port between said passage and exhaust manifold to allow the circulation of exhaust gases to and from said riser, and means for controlling the passage of exhaust gases through said auxiliary passage.
10. In combination with an internal combustion engine having intake and exhaust manifolds and two valves in said exhaust manifold for directing the gaseous medium passing therethrough against a portion of the induction system to cause a heating of the engine fuel, one valve positioned at either side of the discharge opening of the exhaust manifold.
11. The combination with an internal combustion engine, having intake and exhaust manifolds, a riser forming a continuation of said intake manifold, a pair of valves in the exhaust manifold, one at either side of said riser, for directing the gaseous medium passing through the exhaust manifold against said riser to cause a heating of the engine fuel.
12. In combination with an internal combustion engine having intake and exhaust manifolds, a riser connected to said intake manifold and passing through said exhaust manifold, and a plurality of valves in said exhaust manifold to direct all or a part of the exhaust gases against the riser.
13. In combination with an internal combustion engine having intake and exhaust manifolds, a riser connected to said intake manifold and passing through said exhaust manifold, and two valves positioned at opposite sides of said riser in said exhaust manifold to direct all or a part of the exhaust gases against the riser.
14. In combination with an internal combustion engine having intake and exhaust manifolds, a riser from the carburetor to the intake manifold passing centrally through the exhaust manifold, an auxiliary passage formed with said exhaust manifold and positioned centrally longitudinally thereof and extending to opposite sides of said riser, a port between said passage and exhaust manifold to allow the circulation of exhaust gases to and from said riser, and a plurality of valves in said exhaust manifold for controlling the passage of exhaust gases through said auxiliary passage.
15. In combination with an internal combustion engine having intake and exhaust
- manifolds, a riser from the carburetor to the intake manifold passing centrally through the exhaust manifold, an auxiliary passage formed with said exhaust manifold and positioned centrally longitudinally thereof and extending to opposite sides of said riser, a port between said passage and exhaust manifold to allow the circulation of exhaust gases to and from said riser, and means for controlling the passage of exhaust gases through said auxiliary passage, said means comprising a plurality of valves in said exhaust manifold capable of being independently moved to either close said exhaust manifold or to close said passage.
- In testimony whereof I affix my signature.
- EINAR WALLER.
